ADJUSTABLE GAUGE

Robert C. Smith, New Haven, Conn.

Application September 22, 1942, Serial No. 459,245

2 Claims. (Cl. 33—168)

The present invention relates to improvements in adjustable gauges for determining whether or not items of mass production are dimensioned within predetermined tolerances. Such gauges are commonly referred to in the art as "go" and "no-go" gauges, inasmuch as they provide two pairs of complementary gauging-points between one pair of which the item to be gauged should readily fit but not between the other complementary pair of gauging-points.

One of the objects of the present invention is to provide a simple, effective and accurate adjustable gauge of the character referred to, and which may be produced at a low cost for manufacture.

Another object of the present invention is to provide a superior adjustable gauge having two pairs of complementary gauging-points and which may be produced substantially in its entirety from plate metal and hence at low cost.

A further object of the present invention is to provide a superior adjustable gauge of the character referred to, which will provide adjustability over a wide range to thus permit its use for a wide variety of gauging operations.

Still another object of the present invention is to provide a superior adjustable gauge of the character referred to and so constructed and arranged as to adapt it for use either as an internal or external gauge.

With the above and other objects in view, as will appear to those skilled in the art from the present disclosure, this invention includes all features in the said disclosure which are novel over the prior art.

In the accompanying drawing, in which certain modes of carrying out the present invention are shown for illustrative purposes:

Fig. 1 is a face view of one form of an adjustable gauge constructed in accordance with the present invention;

Fig. 2 is a view looking toward the lower edge thereof;

Fig. 3 is a view looking toward the right-hand edge of Fig. 1;

Fig. 4 is a transverse sectional view taken on the line 4—4 of Fig. 1;

Fig. 5 is a detached perspective view of one of the interchangeable L-shaped gauging-members detached;

Fig. 6 is a perspective view of the plate-like body-unit;

Fig. 7 is a face view of the same character as Fig. 1, but showing a different setting of the gauging-members; and

Fig. 8 is a perspective view of a pair of complementary gauging-members especially designed for gauging the internal diameters of openings or bores.

The particular embodiments of the present in-

vention chosen for illustration in the accompanying drawing, include a rectangular body-unit generally designated by the reference character 10 and comprising a rectangular body-plate 11 and a longitudinal seat-rib 12 united therewith.

Both the body-plate 11 and the seat-rib 12 may be conveniently formed of plate steel and as is particularly well shown in Fig. 6, the seat-rib 12 extends longitudinally of the body-plate 11 and is located centrally intermediate its respective opposite side-edges. The said seat-rib 12 is accurately located with respect to the body-plate 11 by means of a pair of dowel pins 13—13 extending through both of the elements 11 and 12 and respectively located adjacent the respective opposite ends of the body-unit 10. To hold the seat-rib 12 firmly to the body-plate 11, a pair of screws 14—14 are passed through the said seat-rib and threaded into the body-plate 11.

Adjustably mounted on the body-unit 10 in engagement with the front-face of the body-plate 11 and in engagement with the side-edges of the seat-rib 12 are four L-shaped gauging-members 15, 16, 17 and 18. The said gauging-members may each be a duplicate of the others and may be conveniently formed of plate steel preferably of a thickness corresponding to the thickness of the seat-rib 12 and suitably hardened and ground. Each gauging-member includes a bifurcated anchoring-arm 19 extending in parallelism with and having its inner edge tightly seated against the adjacent edge of the seat-rib 12 and having a relatively-deep notch 35 or slot 19a. Extending outwardly at a right angle from its anchoring-arm 19, each gauging-member is formed with an integral rigid gauging-arm 20 projecting beyond the adjacent side-edge of the body-plate 11 for purposes as will hereinafter appear. Each gauging-arm 20 is preferably ground to provide a pair of opposite gauging-surfaces 21 and 22 extending perpendicularly to the side-edges of the seat-rib 12 and in strict parallelism with each other.

As thus constructed and arranged, one of the four gauging-members 15, 16, 17 and 18 is located adjacent each of the four corners of the rectangular body-unit 10.

To provide for the adjustable retention of the gauging-members 15, 16, 17 and 18 in their predetermined location on the body-unit 10, the body-plate 11 of the said body-unit is provided adjacent each of its four corners with one of four corresponding pairs of threaded sockets or bores 55 23 and 24 arranged in alignment with the notch or slot 19a in the adjacent one of the four gauging-members, as is clearly shown in Figs. 1 and 7. Extending through the slot 19a in the bifurcated anchoring-arm 19 of each of the L-shaped gauging-members is a clamping-screw 25 which

enters one or the other of the threaded sockets 23 or 24 in the body-plate 11, in accordance with the desired setting of the gauging-members. Preferably, a relatively-heavy clamping-washer 26 is interposed between the under-face of the head of each of the clamping-screws 25 and the forward face of the adjacent gauging-member.

By loosening its complementary clamping-screw 25, each of the gauging-members 15, 16, 17 and 18 may be moved longitudinally with respect to the body-unit 10 until the appropriate settings are secured. By way of example, the gauging-members 15 and 16 may be set so that their respective gauging-surfaces 21 and 21 are .751" apart in the event that the item to be gauged should have a nominal external size of 3/4", with a tolerance of plus or minus .001". Under the conditions just described, the gauging-members 17 and 18 would be set so that their respective gauging-surfaces 21 and 21 are spaced .749" apart.

As thus set, the gauging-members 15 and 16 would constitute the "go" gauge since it would be intended that appropriately dimensioned articles of manufacture should pass between the opposed gauging-surfaces 21-21 of the said gauging-members 15 and 16. Under these conditions, the gauging-members 17 and 18 would constitute the "no-go" gauge, inasmuch as the properly dimensioned article of manufacture should not pass between the opposed gauging-surfaces 21-21 of the said gauging-members. Where suitable, the respective pairs of gauging-members may be set to employ their gauging-surfaces 22-22 for gauging internal dimensions.

Should it be desired to provide a much greater gap between the gauging-surfaces 21-21 of the complementary gauging-members 15 and 16 or the complementary gauging-members 17 and 18, than the gap provided by the setting shown in Fig. 1, the clamping-screws 25 may be shifted from the threaded sockets 24 and into the outermost threaded sockets 23. If this setting is not adequate for the size of item to be gauged, then each gauging-member may be reversed so that its gauging-arm 20 is located on the outside of the ends of the body-unit 10.

By way of illustrating the versatility of the gauge of the present invention, the parts may be assembled in the manner shown in Fig. 7 so that the pair of complementary gauge-members 15 and 16 may be utilized for gauging a relatively-small dimension, while the pair of complementary gauging-members 17 and 18 may be utilized for gauging a relatively-large dimension.

In instances where it is desired to gauge the internal diameter of cylindrical holes or apertures, a pair of complementary gauging-members 27 and 28, illustrated in Fig. 8, may be employed. Each of the said gauging-members 27 and 28 corresponds generally to the gauging-members previously described and comprises a bifurcated anchoring-arm 29 having a longitudinal slot or notch 29a therein, and a gauging-arm 30. The respective gauging-arms 30 of the gauging-members 27 and 28 are each provided with a cylindrically-contoured gauging-surface 31 and a flat gauging-surface 32, both extending in parallelism with each other and perpendicularly with respect to the anchoring-arm 29.

With the gauging-members 27 and 28 related in the manner illustrated in Fig. 8, the cylindrically-contoured gauging-surface 31 of each of the said

gauging-members is on the outside and may be employed for extension into a cylindrical cavity or bore to gauge the diameter thereof.

In any setting of a given pair of the complementary gauging-members, the edge portions of the seat-rib 12 or its equivalent will serve to ensure the alignment of the said gauging-members in conjunction with the adjacent outer face-ports of the body-plate 11.

By means of the construction and arrangement of parts shown, a highly-versatile gauge is provided which lends itself to production from plate material and at a low cost as compared to most gauges now in use.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An adjustable gauge including in combination: a relatively-wide body-plate; a relatively-narrow seat-rib located on one face of the said body-plate intermediate the respective opposite side-edges thereof so as to leave a portion of the face of the said body-plate adjacent each side-edge of the said seat-rib exposed for engagement by a pair of gauging-members; a pair of L-shaped gauging-members constructed and arranged to be mounted on either of the respective opposite sides of the said seat-rib and each gauging-member including an anchoring-arm having its inner edge seated against one edge of the said seat-rib and having one of its faces bearing against the face of the said body-plate adjacent the said seat-rib, each of the said L-shaped gauging-members also including a gauging-arm extending substantially perpendicularly from its complementary anchoring-arm and projecting outwardly beyond the adjacent side-edge of the said body-plate; and clamping-means adjustably holding the said gauging-members against the said body-plate and against the said seat-rib.

2. An adjustable gauge including in combination: a relatively-wide body-plate; a relatively-narrow seat-rib located on one face of the said body-plate intermediate the respective opposite side-edges thereof so as to leave a portion of the face of the said body-plate adjacent each side-edge of the said seat-rib exposed for engagement by a pair of gauging-members; a pair of L-shaped gauging-members constructed and arranged to be mounted on either of the respective opposite sides of the said seat-rib and each gauging-member including a slotted anchoring-arm having its inner edge seated against one edge of the said seat-rib and having one of its faces bearing against the face of the said body-plate adjacent the said seat-rib, each of the said L-shaped gauging-members also including a gauging-arm extending substantially perpendicularly from its complementary anchoring-arm and projecting outwardly beyond the adjacent side-edge of the said body-plate; and clamping-screws respectively extending through the slotted anchoring-arm of one of the said gauging-members to hold the same against the said body-plate and against the said seat-rib.

ROBERT C. SMITH.
